UNITED STATES PATENT OFFICE.

DARIUS C. BENJAMIN, OF ALPHA, MINNESOTA.

DESIGN FOR A FENCE-STRAND.

SPECIFICATION forming part of Design No. 26,410, dated December 15, 1896.

Application filed October 28, 1896. Serial No. 610,374. Term of patent 14 years.

To all whom it may concern:

Be it known that I, DARIUS C. BENJAMIN, a citizen of the United States, residing at Alpha, in the county of Jackson and State of Minnesota, have invented and produced a certain new and original Design for Barbed-Fence Strips; and I do declare the following to be a full, clear, and exact description of the invention, such as will enable others skilled in the art to which it appertains to make and use the same.

My invention relates to a design for a barbed-fence strip.

It relates to the entire configuration of the strip, and especially to a barbed-fence strip constructed of sheet metal.

My invention relates particularly to a barbed-fence strip as illustrated in the accompanying drawings, in which—

Figure 1 is a perspective view of a strip for barbed fences embodying my design, and Fig. 2 is a front edge view of the same.

The leading features of my design appear in the following description.

1 represents a suitable strip having a straight edge 2, and from the opposite edge project outwardly from one side a series of V-shaped spurs or barbs 3. These barbs are curved at 4, where they integrally join the strip 1, and the sides of their V-shaped edges are arranged at an oblique angle to the length of the strip, the barbs themselves extending outwardly approximately at a right angle to the side of the strip, as shown in the drawings.

Having thus described my design, what I claim, and desire to secure by Letters Patent of the United States, is—

The design for a barbed-fence strip, substantially as herein shown and described.

In testimony whereof I hereunto affix my signature in presence of witnesses.

DARIUS C. BENJAMIN.
